UNITED STATES PATENT OFFICE.

HENRY BUSH SPENCER, THOMAS SHORT, AND NAPOLEON DEROCHER, OF OTTAWA,
ONTARIO, CANADA.

TRAIN-STOP.

1,359,122.

Specification of Letters Patent. Patented Nov. 16, 1920.

Application filed July 26, 1920. Serial No. 399,096.

To all whom it may concern:

Be it known that we, HENRY BUSH SPENCER, THOMAS SHORT, and NAPOLEON DEROCHER, subjects of the King of Great Britain, residents of the city of Ottawa, Province of Ontario, Dominion of Canada, have invented certain new and useful Improvements in Train-Stops, of which the following is a specification.

10 This invention relates to improvements in train stops, and the objects of the invention are to automatically stop a train in the event of the engineer failing to see or hear a signal, to provide means whereby the train 15 stopping device must be manually reset before the train can proceed upon its journey, to permit of the train stopping device being readily mounted on locomotives at present in use and without any alteration of the existing parts, so that the installation will 20 become comparatively simple and cheap to make.

Further objects are to provide a means which will re-place the train stopping device in the event of the latter becoming broken, so that the train will be enabled to complete its journey and until such time as a new train stopping device can be fitted to the train, to simplify the arrangement of 30 the several parts, and generally to adapt them to better perform the functions required of them.

With the above and other objects in view, the invention consists essentially of the improved construction particularly described and set forth in the following specification and accompanying drawings forming part of the same.

In the drawings:

40 Figure 1 is a side elevation of the front portion of a locomotive equipped with our improved train stopping device and showing a torpedo in front of the train.

Fig. 2 is a side elevation of the front end 45 of a locomotive equipped with our improved train stopping device showing the front wheels of the locomotive engaged with the torpedo to explode the same, the concussion of the explosion shattering the frangible 50 wall in the front of the train stopping device and allowing the escape of air from the brake pipe line of the train, resulting in a service application of the brake.

Fig. 3 is a perspective view of the train

stopping device which is adapted to be connected to the brake pipe line of a train. 55

Fig. 4 is an enlarged side elevation of our improved train stopping device showing the clamping member for holding it in position relative to the front wheels of the locomotive and to the track. 60

Fig. 5 is a longitudinal section of a train stopping device illustrated in Fig. 4.

Fig. 6 is a fragmentary sectional elevation of the cap or retaining means, by means 65 of which the frangible glass wall is secured to the front of the train stopping device.

Fig. 7 is a sectional elevation of the cap or retaining means.

Fig. 8 is a transverse section on the line 70 8—8 of Fig. 4.

Fig. 9 is a transverse section on the line 9—9 of Fig. 4.

Fig. 10 is a transverse section on the line 75 10—10 of Fig. 4.

Fig. 11 is a sectional elevation of the cap adapted to be threaded on the end of the brake pipe line in the event of the train stopping device becoming broken.

Like characters of reference refer to like 80 parts in the several figures.

Referring to the drawings; A represents a locomotive of any usual description well known in the art, so that it is deemed unnecessary to describe the same; B represents an extension of the ordinary and well known brake pipe line which is used in railway practice. 85

C represents our improved train stopping device which is adapted to be secured 90 to the end of the brake pipe line B and located adjacent to the front wheel of the locomotive, and in close proximity to the ball of the rail.

This train stopping device comprises a 95 tubular member 10 having a central conduit 11 which is relatively small and would only permit of air escaping from the pipe line B at a velocity of speed to insure a service application of the brakes, when the train 100 stopping device is being operated.

The tubular member 10 has its outer periphery 11 stepped, and is provided intermediate of its length with an annular recess 12, the object of which will be made 105 clear hereafter.

The larger end of the tubular member 10 is provided with a central recess 13, and

the outer periphery of the larger end is threaded. The outer periphery of the smaller end of the tubular member 10 is also threaded, and is attached by a coupling 5 14 to the brake pipe line B.

The front enlarged end of the tubular member 10 is closed by a frangible member 15 preferably of glass which is secured in position by a cap or retaining means 16 10 threaded to the enlarged end of the said tubular member.

So that the glass will make an air tight joint we provide rubber gaskets 17 and 18 or other like packing members on the front 15 and back of the glass and adjacent to the edge thereof, and a thin metallic ring 19 is superposed on the gasket 18, so that when threading the cap 16 into position there is no possibility of the gaskets 17 and 18 be- 20 coming destroyed.

The cap or retaining member 16 is open on the front wall and is formed with only an annular flange on the front which secures the glass 15 in position.

25 This tubular member 10 is angularly disposed in front of the locomotive and located in close proximity to the front wheel of the locomotive and to the ball of the rail, and a suitable clamping member 20 is provided which is bolted or otherwise secured to embrace the annular recess 12 in the tubular member 10.

This clamping member forms a portion of a suitable bracket D which will be secured in such a manner to the front of the locomotive and to make it a rigid and solid job, and in this way the train stopping device C cannot become displaced but will always be in a position ready to be 40 operated.

In railway practice it is common to use torpedoes, and our improved train stop is utilized in conjunction with these torpedoes. When a torpedo is placed upon a rail by 45 a trackman or other person for the object of warning an approaching train, it often happens that the signal is not heard or disregarded.

A torpedo E is shown on the track, and 50 as a locomotive equipped with our improved train stopping device approaches and the front wheel passes over the torpedo E, then the torpedo is exploded, and the concussion shatters the frangible wall or 55 glass 15 allowing air to escape from the brake pipe line B through the conduit 11 and permitting of a service application of the brakes being made, so that the train is slowly brought to a stop.

60 A feature of this invention, which is very important, is that once the glass 15 has been shattered the engine cannot proceed until the engineer descends from the cab and removes the cap or retaining member 16, 65 cleans out the old broken glass from be-

tween the gaskets 17 and 18, positions a new glass in the front of the train stop, and replaces the cap or retaining member 16 in position.

The engineer is thus bound to acknowledge the signal, because his train is automatically stopped and he has the above functions to perform before his train can proceed.

If it should happen that the train stop 75 C became broken, then to permit of the locomotive to proceed to its destination or some other place where a new train stop is obtainable the engineer will close the brake pipe line B by the cap F.

Both sides of the locomotive and the tender, will if necessary, be equipped with the train stop; so that in the event of a locomotive being turned on a turn table or used for backing up purposes or any other 85 function in railway practice the train stop C will always be available or operative.

After the flagman places a torpedo on the rail, he will take up his position the proper distance from the torpedo, flag, or fuze, 90 as per regulations, and when he has the train under control he may remove the torpedo and give the usual hand proceed caution signal until he can converse with the engineer and explain to him why the train has 95 been stopped. On the other hand, if the engineer fails to recognize the flagman's signal and passes the flagman, then the torpedo will stop him in the manner above described and thereby prevent a rear end or 100 other accident.

As many changes could be made in the above construction and many widely different embodiments of our invention within the scope of the claims constructed without 105 departing from the spirit or scope thereof, it is intended that all matter contained in the accompanying specification and drawings shall be interpreted as illustrative and not in a limiting sense.

Another very important feature about our train stop device is, if it so happens that the engine is derailed from some cause or other, the moment the engine drops off the rail the air brakes will apply automatically and bring the train to a stop before there is any loss of life or heavy damage done to equipment or track, or road bed, so much so that the chances are good for the engine and train to stand up or in other words prevent a 115 turn over at an embankment or on the level, because the brake will be automatically applied much quicker than the time it would take the engineer to reach the engineer's valve and he might be unable to reach it at 120 all, by the sudden jolt due to derailment.

Therefore the full meaning of safety first in every sense of the word has been covered and the lives of the engineer and fireman have been saved as well as many other em- 130

ployees and passengers there may be on the train.

What we claim as our invention is:

- 5 1. A train stopping device comprising a tubular member adapted to be connected to the brake pipe line of a locomotive and located in close proximity to the front rail of the locomotive in the direction of travel of the same and in close proximity to the 10 rail, and having a frangible member normally closing the tubular member and designed to be broken by concussion of a torpedo.
- 15 2. The train stopping device claimed in claim 1, in which a frangible member is held in position on the tubular member by a removable cap, and packing members are located adjacent to the frangible member to form an air tight joint.

3. The train stopping device claimed in 20 claim 1, in which a tubular member is secured to a clamping member and held angularly disposed to the rail of the track and to the adjacent wheel of the locomotive.

4. The train stopping device claimed in 25 claim 1, in which the front of a tubular member is provided with a large recess in front of which the frangible member is located, the orifice in the tubular member being relatively small to govern the escape of 30 air from the train line pipe, to permit of a service application of the brakes when the frangible member is broken.

In witness whereof we have hereunto set our hands.

HENRY BUSH SPENCER.
THOMAS SHORT.
NAPOLEON DEROCHER.
